G. EGLOFF ET AL

APPARATUS FOR CRACKING OIL

Original Filed March 23, 1921

UNITED STATES PATENT OFFICE.

GUSTAV EGLOFF AND HARRY P. BENNER, OF CHICAGO, ILLINOIS, ASSIGNEES TO UNIVERSAL OIL PRODUCTS COMPANY, OF CHICAGO, ILLINOIS, A CORPORATION OF SOUTH DAKOTA.

APPARATUS FOR CRACKING OIL.

Application filed March 23, 1921, Serial No. 454,846. Renewed January 14, 1926.

This invention relates to improvements in apparatus for cracking hydrocarbon oils and refers more particularly to that type of apparatus in which the oil is fed continuously through a heating coil and thence to an expansion chamber where vaporization takes place.

The object of the present invention is to provide more effective means for handling the carbon precipitated in the expansion chamber so as to permit of a much longer operation of the process without the necessity of shutting down for cleaning.

In the drawing, the single figure is a view, partly in vertical section and partly in side elevation, of our improved apparatus.

Referring in detail to the drawings, 1 designates the furnace having stack 2, 20 burner 3 and combustion space 4. In the stack is mounted the heating coil 5 which may take the form of a continuous length of coil of say, 4" diameter, having 1500 square feet of heating surface. The inlet 25 side of this coil is connected by feed line 6 to the charging pump 7 leading to any suitable source of supply. The discharge side of the coil is connected by transfer line 8 to the elongated expansion chamber 9, 30 which may take the form of a cylindrical drum eight feet in diameter and fifty feet long, having a capacity of over 100 tons of carbon when full. This drum is provided with a vapor outlet pipe 10 extending into 35 the upper end of a dephlegmator 11, the pipe 10 having spaced cap member 12 to prevent the reflux condensate from falling back into the chamber 9. The dephlegmator 11 is provided with a plurality of spaced 40 foraminated or perforated plates 13. It also has reflux return pipe 14 leading back to the feed line 6. The upper end of the dephlegmator is connected by pipe 15 to condenser coil 16 seated in condenser box 17. 45 The lower end of the coil is connected by pipe 18 to the top of receiver 19. This receiver 19 has pressure gauge 20, liquid level gauge 21 and gas outlet pipe 22, distillate drawoff pipe 23. Various parts of 50 the system are provided with throttle valves 24 for maintaining suitable vapor pressure on the system as shown in the drawings.

Referring back to the expansion chamber 9, it is provided with a plurality of re-

siduum drawoffs or outlets 25, these being 55 spaced, for example, equi-distant apart and extending across the lower end of the expansion chamber, there being in the present instance, six. These residuum outlets consist of flanged bosses 28 connected to a 60 tapered flanged pipe section 29 suitably secured to the bosses 28. The lower end of the members 29 are connected through the throttle valves 30 to a residuum header 31. This residuum header 31 is provided at its 65 outlet side with a master throttle valve 32 and is connected to any suitable residuum storage. In order to facilitate the removal of the carbon-containing residue from the header, I provide a compressed air or high 70 pressure steam line 33 having a throttle valve 34 and leading to any suitable source of air or steam under pressure.

The arrangement is such that the residuum can be drawn off from all of the outlets 75 25 or through any one or more of them as desired. This allows of considerable flexibility in treating and drawing off carbon deposits during the run as all the carbon 80 may be removed from that portion of the still, by opening any one of the six residuum outlets shown. By alternately opening and closing these drawoffs, the expansion chamber may be kept free from carbon over 85 a long period of time.

In operating the process, Wayside Kansas fuel oil or the like may be fed continuously through the heating coil and heated to a temperature in the transfer line of about 870 degrees F. and the whole system maintained 90 under a vapor pressure of 145 pounds. The operation may be continued until, say, 70 or 80 tons of carbon are deposited in the expansion chamber, it being understood that 95 while a great part of the carbon may be continuously drawn off, it is impossible to draw it all off during the operation of the apparatus so that some carbon will continue to accumulate. A half million gallons of oil 100 could be run through the apparatus described before it would be necessary to shut the apparatus down for cleaning.

We claim as our invention:—

1. In an apparatus for cracking oil, the combination with a heating coil, of an expansion chamber connected thereto, said expansion chamber taking the form of a large elongated shell and provided with a plural-

ity of valve controlled residuum drawoffs and a residuum header connected to the drawoffs, and means for forcing fluid under pressure through the header to rapidly withdraw residuum from said expansion chamber.

2. In an apparatus for cracking oil, the combination with a cracking coil through which oil is passed to be subjected to cracking conditions of temperature and pressure, an expansion chamber receiving said oil, a plurality of discharge members disposed in spaced relation extending from the lower part of said expansion chamber, valves in each of said members, a header common to all members, and means for introducing a

fluid current to said header to assist in withdrawing the residuum from the expansion chamber.

3. In an apparatus for treating oil, the combination with a heating coil through which oil is passed to be subjected to heat, an enlarged chamber receiving said oil, a plurality of discharge members disposed in spaced relation from the lower portion of said enlarged chamber, valves in each of said members, a header common to all members, and means for introducing a fluid current to said header to assist in withdrawing residuum from the expansion chamber.

GUSTAV EGLOFF.
